UNITED STATES PATENT OFFICE

JAMES M. HARVEY AND JOHN A. HARVEY, OF OGDEN, KANSAS.

HAY AND GRAIN STACKER.

1,113,988.

Specification of Letters Patent. Patented Oct. 20, 1914.

Application filed November 26, 1912. Serial No. 733,605.

To all whom it may concern:

Be it known that we, JAMES M. HARVEY and JOHN A. HARVEY, citizens of the United States, and residents of Ogden, in the county of Riley and State of Kansas, have invented certain new and useful Improvements in Hay and Grain Stackers, of which the following is a specification.

Our invention relates to stackers for hay, grain, straw, leaves and the like, and possesses quite a number of distinct advantages, being especially adapted for forming stacks of large size and being easily operated by aid of a minimum expenditure of labor.

15 Reference is made to the accompanying drawings forming a part of this specification and in which like letters indicate like parts.

Figure 1 is a plan view of our stacker complete; Fig. 2 is a rear elevation of the same; Fig. 3 is a detail showing in section the jointed platform for elevating, supporting, conveying and discharging the material to be stacked; Fig. 4 is a detail showing in fragmentary perspective a portion of the jointed platform; Fig. 5 is a side elevation showing the stacker complete as it would be seen from a point at the left of Fig. 1; Fig. 6 is a plan view of the jointed platform; Fig. 7 is a perspective showing the vertically adjustable frame for virtually controlling the height of the stack; Fig. 8 is a detail showing a tripping lever and parts associated therewith for practically controlling the hooks used in tilting or unloading the platform. Fig. 9 is a detail showing in perspective one of the parts appearing in Fig. 8.

Connected with a number of longitudinal beams 10 are cross beams 11, these parts together forming a flat skeleton frame which is strengthened by truss rods 10^a. Mounted upon the cross beams 11 are bearings 12 through which extends a shaft 13 carrying wheels 14, the latter engaging tracks 15 which rest upon the ground or upon any suitable supporting surface. Extending upwardly from the edge of the frame are standards 16-17-18-19. An engine 20 is supported by the frame and movable bodily therewith. This engine is provided with a driving pulley 21 and from this pulley a belt 22 extends to another pulley 23, the latter being mounted rigidly upon a revolute shaft 24. This shaft is journaled

in bearings 24^a carried by the standards 16-17-18-19.

At 25-26 are two pulleys mounted loosely upon the shaft 24, and at 27-28 are two clutches for securing the pulleys rigidly in relation to the shaft 24. A clutch fork is shown at 29 and is connected to both of the clutches. A lever 30 is connected with the fork 29 to enable the operator to control the clutches. Below the lever 30 and supported upon two of the cross beams 11 is a floor 31 upon which the operator stands.

A crossed belt 32 engages a pulley 26 and a pulley 34. Another belt 33 engages the pulley 25 and pulley 35. The pulleys 34-35 are mounted rigidly upon a shaft 36. This shaft carries a gear pinion 37 which meshes with a gear wheel 38, the latter being mounted rigidly upon the shaft 13. Motion is transmitted from the shaft 24 to the shaft 13 and thence to the wheels 14, the direction of rotation of the latter being dependent upon the position of the clutch lever 30.

Mounted upon the shaft 24 is a sprocket gear 39 which engages a sprocket chain 40, the latter engaging a sprocket gear 41. This sprocket 41 is mounted rigidly upon a shaft 42, the latter carrying a gear pinion 43, which meshes with a gear wheel 44. 85 Connected rigidly with this gear wheel is a hoisting drum 45. Upon the front of the machine is a small fork 46 which serves as a pilot for sweeping the scattered hay or other material from the adjacent track 15. 90 This pilot is connected by a pivot 47 with the frame yoke, as will be understood from Fig. 5.

Extending upwardly from the frame 10 are beams or posts 49 spaced apart and braced by ties 48-50 and together with the latter constitute a vertically disposed slideway of considerable height. Connected with the upper portion of this slideway and extending obliquely downward therefrom to the beams 10 are braces 51-52 which serve to hold the slideway firmly in position. A sliding frame 53 is mounted in the slideway and is adjustable to different elevations. The sliding frame 53 (see Fig. 7) is provided with the bottom bar 53^a and also provided with a pair of extending rails 54, these rails being horizontal, whereas the frame 53 is vertical.

A pulley 57^a is mounted upon the beam 110

57, at a point near the tripping member 77. Connected with the tripping member 77 and engaging the pulley 57^a is a cord 77^a. This cord also engages pulleys 77^b, 77^c and 77^d, 5 and is secured to a lever 77^e, which controls the hoisting mechanism including the hoisting drum 45.

Bracing rods 55—56 extend from the top of the sliding frame 53 to the rails 54 and 10 serve to support the same at their outer ends. Extending across the rails 54 is a beam 57 which carries a plate 58, and extending obliquely from this plate to the rails 54 are a pair of brace rods 58^a. Revolubly 15 mounted upon the beam 57 are grooved pulleys 59 and adjacent to these pulleys are other grooved pulleys 60. Located near the ends of the rails 54 are pulleys 61—62. Engaging the pulleys 61 and 59 are cords 63. 20 Cords 64 engage the pulleys 60 and 62. The cords 63—64 extend downwardly and are used in handling the jointed platform, as hereinafter described. The cords 63—64 are all connected with a cable 65 which extends 25 over a drum 66 and downwardly from the latter to the hoisting drum, 45, above described. The drum 66 is located above the hoisting drum and is journaled to rotate freely in a frame 67, this frame being carried by the sliding frame 53, as will be understood from Fig. 7.

The rails 54 are supported upon the under side by rigid braces 68 which extend obliquely upward from the vertical frame 35 above described. Mounted upon one of the rails 54 are two hooks 69 provided with upwardly extending portions 70. These hooks are adapted to rock and are provided with torsion springs 69^a which normally tend to 40 hold the hooks in such position that their lower ends extend slightly forward, that is, toward the front of the machine according to Fig. 1. Their purpose is to facilitate the entrance of the lower ends of the hooks 45 into the openings 90 when the load is to be discharged. To the upwardly projecting portions 70 of the hooks are attached a pair of contraction springs 69^b. The purpose of these springs is to provide means 50 whereby either hook can be manipulated should it at a particular moment happen to be hanging free and the other hook caught. These springs are connected to cords 71 which extend directly across and are connected to bell crank levers 72, the latter being mounted upon pivot pins 73. A spring is shown at 74 (see Fig. 1) and tends to hold the bell crank levers 72 in their normal retracted positions. A cord 75 extends from 55 one of these bell crank levers to the other and is connected to a cord 76 which engages pulleys 76^a—76^b and is operated as hereinafter described for the purpose of manipulating the hooks 69.

65 Mounted upon the cross beam 57 (see Figs.

1 and 5) is a tripping member 77 having substantially the form of a triangular saddle. This tripping member is movable relatively to the cross beam 57 and is connected to the same by a pivot 78. A turn-buckle 70 53^b and guys 53^c are used for bracing the vertical movable frame 53, the guys and turn buckle being subjected to a tensile strain.

Another cord 77^c is within reach of the operator standing upon the floor 31 and is pulled by a hand in order to actuate the controlling lever 77^e. Another cord 77^d is connected with the lever 77^e and is used for pulling by hand in a direction opposite to that in which it is pulled by the cord 77^c. When the lever 77^e is pulled to the left, according to Fig. 1, the hoisting mechanism including the drum 45 is thrown out of action and whenever the lever 77^e is shifted to the right, according to Fig. 1, by a pull upon the cord 77^c the hoisting mechanism is thrown into action. As the controlling lever 77^e, and connections whereby it controls the hoisting drum 45 are old and well known, we will not describe these parts in detail.

We will now describe the jointed platform used for retaining temporarily the material to be operated upon in order to lift this material to the proper height and to deposit it upon the stack. The jointed platform has generally the form shown in Fig. 6. It comprises a number of longitudinal sills or ribs 79 upon which the material to be operated upon may be raised directly. In the present 100 instance we employ a number of webs 80 of sheet metal which extend from sill to sill and are useful for preventing the dropping of fragmentary portions of hay or other material. The webs may be employed or 105 not as desired. The two outermost sills are shown at 81 and are provided with extending portions 82. The front ends of the sills are secured to a bar 83 made in two pieces supported by a truss rod 83^a. Mounted and 110 connected upon this bar are straps 84 carrying clevises 85 to which the cords 63—64 are attached. Abutting the webs 80 are shorter webs 86, two of the latter being provided with openings 87. The webs 86 115 may be somewhat thicker than the webs 80 if desired. The openings 87 are for the purpose of temporarily receiving the wheels of the push rake as the latter is driven on to the jointed platform. Connected with the 120 webs 86 are hinges 88 and secured to these hinges is a board 89 which is provided with slots 90. By aid of the hinges 88 the board 89 can be tilted relatively to other parts of the jointed platform and may under suitable 125 conditions assume the position indicated in Fig. 3.

The degree of inclination which the board 89 may assume relatively to the general horizontal plane of the jointed platform is lim- 130.

ited, however, by chains 82^a, as indicated in Fig. 3. The board 89 is provided at its ends with extending portions 91 which carry rings 92 whereby the board and adjacent portions of the jointed platform are normally sustained. Mounted upon a pivot pin 94 carried by one of the cross beams 11 is a lever 95. Connected with this lever is a rod 96, the latter being secured by a pivot connection 97 with one side of the cross beam 11, as indicated more particularly in Fig. 8.

Separate from the other parts of the machine is a beam 98 which is supported upon feet 99 resting directly upon the ground, as indicated in Fig. 9. Connected with the beam 98 is another beam 100 which is beveled off at its outer or free end and is slightly inclined. The beams 98—100 and feet 99 together constitute a type of horse which serves to some extent the purpose of a cam for raising and lowering the lever 95. The horse stands directly upon the ground and is located at one corner of the machine. As the machine travels in one direction upon the tracks 15 the lever 95 is at its outer end engaged by the upper surface of the beam 100 and thereby tilted. When however, the machine travels in the opposite direction, the lever 95 first resting upon the beam 98 glides along the top surface of the beam 100 and is thus released from engagement with the horse.

For the purpose of raising and lowering the sliding frame 53 in order to adjust the height of the rails 54 and parts associated therewith from the ground, we provide pulleys 101—102 and cords 103, the pulleys 101 being secured upon the stationary frame work and the pulleys 102 being connected with the bottom rail 53^a of the sliding frame. A cord 104 (see Fig. 1) is connected with the cord 76 and is under control of the operator who by pulling upon it can actuate the cord 76 independently of the lever 95.

The operation of our device is as follows: The machine is brought into its normal position, that is, facing toward the left, according to Fig. 5. The lever 95 now has its outer end raised and supported by the beam 98, as will be understood from Fig. 8, so that the cord 76 is now drawn tight and as a consequence the bell crank lever 72 (see Fig. 1) and the hooks 69 occupy their abnormal positions—the hooks being swung upwardly at their lower ends,—that is, to the right according to Fig. 5, and thus removed from the vertical path of travel of the fork. The jointed platform rests upon the ground, as indicated in Fig. 6. The hay or other material having been previously loaded upon a push rake propelled by horses, the push rake is driven out upon the jointed platform so that the wheels of the rake enter the openings 87, indicated in Fig. 8. This insures precision in the position of the rake rela-

tively to the jointed platform. The rake is now backed off, that is moved to the right, according to Fig. 6, so as to leave the load of hay resting upon the jointed platform.

We find that in thus depositing materials upon the jointed platform such materials are arranged with more or less semblance toward system, the straws or stems lying crosswise of the sills of the platform. The rake being backed off and cleared of the platform, the operator standing upon the floor 31 pulls upon the cord 77^a thereby shifting the position of the hoisting lever 77^b and throwing the hoisting mechanism into action, the jointed platform being raised vertically upward from the ground. In doing this the board 89 is tilted, as indicated in Fig. 5.

Just before the jointed platform reaches the upper limit of its travel, the board 89 comes into engagement with the lower surface of the tripping member 77 and by tilting it upward pulls upon the cord 77^a. This cord pulls the lever 77^b to the left, according to Fig. 1, and by so doing throws the hoisting mechanism out of action so that the jointed platform is brought to a stop. The operator now moves the lever 30 so as to bring the clutch 27 into action. Power from the engine is now transmitted through the shaft 24, pulley 25, belt 33, pulley 35, shaft 36, gear members 37—38 and shaft 13 to the wheels 14. The machine is thus propelled forwardly (to the left, according to Fig. 5) the track sweeper 46 or pilot having a tendency to clear away any obstacles in front of the machine, or at least lying upon the adjacent rail 15. The machine having traveled to the point where the operator desires the material operated upon to be deposited, the operator again moves the lever 30. By so doing he disengages the clutch 27 and thus disconnects the train of gearing including the wheels 14, so that the rotation of the shaft 24 is now unable to change the position of the machine.

The operator next pulls upon the cord 77^a and in so doing shifts the lever 77^b. This starts the hoisting mechanism into action so that the fork is lowered. The hooks 69 are now hanging directly downward and as the jointed platform is lowered the hooks extend through the slots 90 and prevent the adjacent end of the jointed platform from descending farther. The opposite edge of the platform, to wit, the one at the left, according to Fig. 6, continues to descend, and this causes the entire jointed platform to tilt so that the load of material carried by it glides off the jointed platform and on to the stack. The operator by aid of the cord 77^a now brings the lever 77^b to its normal position, thus stopping the hoisting mechanism. By pulling further upon the cord 77^a he shifts the lever 77^b and the hoisting mechanism is again thrown into action so

as to raise the jointed platform to the position which it occupied before it began to descend. The operator next shifts the lever 30 so as to throw the clutch into action. The power is now transmitted from the engine through the various gear members to the wheels 14 and the machine travels backwardly into the position which it originally occupied. As it approaches said position the lever 95 is again brought into engagement with the beams 100-98 and is tilted so that the cord 76 is tightened, the bell crank levers 72 being thereby dropped into abnormal position, and the hooks 69 being thrown outwardly at their lower ends, as indicated in Fig. 5 so as to clear the path of travel of the jointed platform. The jointed platform is now lowered, and the process repeated, until the stack is built up 20 to the desired height.

As will be understood from the foregoing description a stack of very large size, may be formed, material being placed along it at an infinite number of points forming a row 25 parallel with the tracks. As the tracks can be easily moved and as the material can be deposited at practically any desired height, there is virtually no limit to the proportions which may be given to the stack. We find 30 moreover that where the material operated upon consists of or contains a large portion of stems, these stems are so arranged as to form a very effective thatch or roofing so that even if the stack remains unfinished it 35 is almost water proof.

It will be understood of course that while the machine is in operation the engine 20 is kept running constantly. It supplies power both for shifting the position of the machine and for raising and lowering the jointed platform.

We have for convenience merely shown a typical form of the apparatus, but it should be understood that we are not limited to the 45 precise construction shown. As the lower ends of the cords 63-64 are easily disengaged from the jointed platform a sling or other equivalent for the jointed platform may be employed in its stead if desired.

50 We do not limit ourselves to the precise construction shown, as variations may be made therein without departing from the spirit of our invention.

What we claim as new and desire to secure by Letters Patent is as follows:

55 1. A stacker comprising an elevated supporting member, a platform provided with a plane portion and with a tilting portion movably connected with said plane portion, means for raising and lowering said platform, mechanism carried by said elevated supporting member for engaging said movable portion of said platform so as to sustain said movable portion on said platform, and means for lowering the portion of said

platform opposite said movable portion thereof in order to tilt said platform.

2. A stacker comprising a traveling framework, an elevated supporting member carried thereby, a platform movable relatively to said elevated supporting member, hooks mounted upon said elevated supporting member and adapted to engage a portion of said platform in order to cause said platform to tilt, and means controllable by the travel of the machine for throwing said hooks out of the path of travel of said fork.

3. A stacker comprising a carriage provided with wheels for engaging a track, a framework mounted rigidly upon said traveling carriage and provided with a vertically disposed slideway, a sliding frame mounted in said slideway and carrying horizontal rails extending laterally to the line of travel of the carriage, means controllable at the will of the operator for adjusting the said sliding frame to different heights relatively to said framework, a jointed platform for holding the material to be stacked, and a plurality of flexible 90 connections supported by said horizontal rails and secured to said jointed platform, and mechanism controllable by the operator for virtually varying the length of said flexible connections in order to raise and lower 95 said jointed platform.

4. A stacker comprising a traveling carriage resting upon a track and movable relatively to the same, a framework mounted rigidly upon said carriage and provided 100 with a vertically disposed slideway, a sliding frame mounted in said slideway and having horizontal rails extending at right angles to the general path of travel of said carriage, hoisting mechanism, a jointed 105 platform movable vertically by said hoisting mechanism, and means common to said hoisting mechanism and said carriage for actuating the same either simultaneously or separately at the will of the operator.

5. A stacker comprising a traveling carriage, an elevated supporting member carried thereby, hoisting mechanism, a jointed 110 elevating platform movable vertically toward and from said elevated supporting member by means of said hoisting mechanism, means common to said carriage and said hoisting mechanism for actuating the same so as to tilt said platform in the general direction of the travel of the carriage 115 and at points lateral to said path of travel of said carriage.

6. A stacker comprising a track, a carriage resting upon said track and movable relatively to the same, a framework mounted rigidly upon said carriage and provided with a vertically disposed slideway, a sliding frame mounted in said slideway and provided with rails extending horizontally 125 in a direction lateral to the general path of 130

travel of said carriage, a jointed platform for handling the material to be stacked, said platform being movable vertically toward and from said rails, hoisting mechanisms connected with said jointed platform, and a prime mover common to said carriage and to said hoisting mechanism for actuating the same.

7. A stacker comprising a traveling carriage, a framework mounted rigidly upon said carriage and provided with a vertically disposed slideway, a sliding frame mounted in said slideway and provided with horizontally disposed rails extending laterally

from the path of travel of the carriage, a jointed platform for holding the material to be stacked, said platform being movable vertically toward and from said rails, hoisting mechanism for said platform, and means controllable at the will of the operator for 15
tilting said platform in the general direction of travel of the carriage and at points located laterally to said path of travel.
